Application July 19, 1935, Serial No. 32,148

12 Claims. (Cl. 112—2)

Our invention relates to sewing machines. More particularly, our invention is concerned with improvements to that type of sewing machine used for making neckties, and disclosed in 5 our Patent No. 1,931,447, dated October 17, 1933, in which there is employed a double pointed needle having its eye located between the points, the opposite ends of which are grasped alternately by the jaws of opposed needle bars arranged in alignment.

One object of our invention is to provide a machine of the character described, having improved threading mechanism by means of which we are able to quickly thread the needle.

Another object of our invention is to provide a machine of the character described having improved thread holding means making it unnecessary for the operator to secure or release the thread.

Another object of our invention is to provide a machine of the character described in which the thread is prevented from becoming entangled and thereby broken, during the stitching operation.

Another object of our invention is to provide a machine of the character described, having improved looping mechanism.

Still another object of our invention is to provide a machine of the character described, having means to facilitate the quick removal and replacement of the needle.

A further object of our invention is to provide a machine of the character described in which the free end of the thread that is wound on the drum is prevented from becoming entangled with adjacent strands of thread wound on the drum.

A further object of our invention is to provide a machine of the character described having improved work feeding mechanism.

Another object of our invention is to provide a machine of the character described, having means whereby the needle on its down stroke is assured against piercing and therefore breaking the thread.

Still another object of our invention is to provide a machine of the character described having automatic means for starting the tie stitching operation and for stopping when the tie has 50 been completely stitched.

Other objects of this invention will in part be obvious and in part hereinafter pointed out.

The invention accordingly consists in the features of construction, combinations of elements, and arrangement of parts which will be exem-

plified in the construction hereinafter described, and of which the scope of application will be indicated in the following claims.

In the accompanying drawings, in which is shown one of the various possible illustrative embodiments of this invention:

Fig. 1 is a plan view of the assembly of the apparatus embodying our invention;

Fig. 2 is a view similar to Fig. 1 but in side elevation;

Fig. 3 is a side view of a portion of the apparatus, partly sectional, disclosing some of the features of our invention;

Fig. 4 is a detail view of a clutching mechanism employed in our invention;

Fig. 5 is an enlarged view in section of one of the details of our apparatus;

Fig. 6 is a view in section, taken substantially on the line 6—6 of Fig. 5;

Fig. 7 is a front view similar to Fig. 3;

Fig. 8 is a view in detail of a portion of the apparatus shown in Fig. 7;

Fig. 9 is a view in section, taken substantially on line 9—9 of Fig. 7;

Fig. 10 is an enlarged detail, in section, of a portion of our apparatus illustrating one of the elements of the operation of the mechanism embodying our invention;

Fig. 11 is an enlarged detail in section of a portion of our apparatus illustrating another element of the operation of the mechanism embodying our invention;

Fig. 12 is a detail in section taken substantially on the line 12—12 of Fig. 11;

Fig. 13 is an enlarged detail in section of a portion of our apparatus illustrating another element of the operation of the mechanism embodying our invention;

Fig. 14 is a plan view in elevation of a portion of our apparatus;

Fig. 15 is an enlarged detail in section of a portion of our apparatus illustrating another element of the operation of the mechanism embodying our invention taken substantially on the line 15—15 of Fig. 14;

Fig. 16 is an enlarged detail in section of a portion of our apparatus illustrating another element of the operation of the mechanism embodying our invention;

Fig. 17 is a detail view in section, taken substantially on the line 17—17 of Fig. 16; and

Fig. 18 is a wiring diagram illustrating one feature of our invention.

Referring to the drawings, wherein we have disclosed the apparatus embodying our invention;

tion, and more particularly to Fig. 3, we will first describe the operation of the driving mechanism by means of which the needle is caused to be alternately grasped by the jaws of the upper and lower needle bars. There is provided suitable driving means such as a motor M, supported on a bracket 25. Mounted on motor shaft 26 is a gear 27 meshing with a gear 28 which is mounted on shaft 29, suitably supported as shown, said shaft 29 having also mounted thereon a pulley 30. Pulley 30 may be made to drive pulley 32 by means of a belt 31. Pulley 32 is freely supported on a fixed, non-rotatable shaft 33 which is held in a support 34 fixed to the casing C. Positioned between pulley 32 and shaft 33 there is provided a collar 35 integral with and extending laterally from pulley 32, said collar being adapted to rotate freely on shaft 33. Mounted on said collar 35 for rotation therewith is a gear 36, cam 37 and cam 38. By this construction it is seen that cams 37 and 38, and gear 36 are integrally connected to move as a unit when pulley 32 is driven by the belt 31. Said cams 37 and 38, as well as gear 36 are fixedly mounted on collar 35 which is designed to rotate freely about shaft 33. Cam 38 is provided with an annular groove in which rollers 39 are guided, said rollers being mounted on shafts 40 fixed to plate 41. It is seen from the above construction that plate 41 will be caused to oscillate with a predetermined regularity in accordance with the path of the annular groove in cam 38. This predetermined degree of oscillation of plate 41 may be made to be of the same amount as desired for the oscillation of upper needle bar 50 and lower needle bar 51 to alternately clutch the double pointed needle 52 after it has pierced the material to be stitched. The oscillatory motion of plate 41 may be transmitted therefrom to needle bars 50 and 51 by means such as rocker arms 53 and 54 pivoted to the casing at 55 and 56, respectively. Rocker arm 53 is connected to needle bar 50 by means of a link 57 and to plate 41 by means of a link 58, while rocker arm 54 may be connected to lower needle bar 51 by means of a link 59, and to plate 41 by means of a link 60.

During the operation of our apparatus, as fully described in our Patent No. 1,931,447, it was found that much time was lost by the operator in the threading of the needle and in securing one end of the thread in a fixed position until the stitching of the tie had been completed, at which time the thread had to be released by some means such as cutting with a knife or breaking.

We have therefore devised a novel mechanism by means of which the needle may be quickly threaded, after which one end of the thread is automatically grasped and held until the stitching of the tie has been completed, at which time the held thread is then automatically released. The mechanism by which we accomplish this may be described as follows:

65 A threader 65 (see Fig. 3) having a threading hook 66 at one end and a handle 167 at the other end, is pivotally mounted on a shaft 168 fixed to upper rocker arm 53. By this construction it is seen that hook 66, which is adapted to pierce the eye of the needle 52 to thread it, will always be in proper position to pierce the eye of the needle 52 when said needle is clutched by the upper needle bar 50. This is due to the fact that shaft 168 about which the hook 66 is pivoted is caused to move with nee-

dle bar 50 to maintain a constant distance between shaft 168 and the eye of the needle.

In Figs. 16 and 17 of the drawings we have shown the hook portion 66 of threader 65 after it has been swung around to pierce the eye of the needle 52. Thread T which is shown looped over the hook, is ready to be threaded in the eye of the needle.

By referring to Figs. 3 and 15 it will be noted that a pair of jaws 67 and 68 of a grasping device 70 supported on the machine casing, are shown held in effective or closed position by the action of a spring 71, whereas in Fig. 16 it is seen that when the threader hook 66 has been inserted through the eye of the needle, the jaws 67 and 68 of the grasping device 70 have been forced open by means of a cam 69 rotatably mounted on threader 65 and adapted to ride on lower jaw 68 to force said jaw 68 downwardly against the action of spring 71. As the threader 65 is pulled back to be withdrawn from the eye of the needle, hook 66 carries one end of the thread through the eye of the needle to thread the same and thence between the opened jaws 67 and 68. At the same time cam 69 allows lower jaw 68 to resume its normally closed position to grip the thread T between the teeth of the upper and lower jaws 67 and 68 to hold said thread in a fixed position. One end of thread T is thus held fixed for a predetermined time, such as when the tie has been completely stitched, when it is automatically released. We have provided the following means for automatically releasing the held thread at such predetermined time. A vertical plate 72 is mounted on an intermittently traveling work carriage 73. The mechanism by which this work carriage is moved will become apparent as the description proceeds. Attached to plate 72 is a track 74 inclined with respect to the horizontal and suitably positioned and adapted to have a roller 75 ride thereon, said roller 75 being rotatably mounted to the extended end of lower jaw 68 (see Fig. 16). Lower jaw 68 is made to pivot about an axis 76. When the work carriage 73 travels in the direction of the arrow 45 (Fig. 7) for a predetermined distance, roller 75 will ride on inclined track 74 to cause lower jaw 68 of the grasping device 70 to automatically release the thread T.

In stitching machines of the type described, wherein a looper is employed and where the loose end of the thread is pulled through the work after the completion of each stitch, it is particularly desirable to provide means to prevent the two strands of the thread cooperating with the needle and the work from becoming intertwined or entangled. Should the thread become entangled the looper or the thread puller would tend to engage both strands of thread, and since one end of the thread is held fixed it would be broken thus causing delay and inefficiency. To obviate this disadvantage we have devised novel thread holding mechanisms designed to constantly maintain the thread in position to prevent tangling. We will first describe the operation of our thread holding mechanism as applied to the needle when said needle is connected to the upper needle bar 50. Then the operation of the mechanism which we employ to hold the thread when the needle is connected to the lower needle bar 51 will be described.

In Figs. 7 and 8 of the drawings there is disclosed upper needle bar 50 slidably operating in the frame C, said frame having attached thereto

a bracket 80. An arm 81 is pivoted at one end to bracket 80 at a point 82. Arm 81 may be held pressed into engagement with needle 52 by suitable means such as an adjustable spring 83. A 5 stop 84 fastened to the frame of the machine is provided to limit the pressure of arm 81 against the needle 52 to prevent breaking of the needle. On the opposite side of the needle 52 from that 10 of arm 81 we provide another arm 86, pivotally mounted on the machine casing at 87 and held in engagement with needle 52 by suitable means such as a spring 88. Arm 81 is provided with a cam portion 85 adapted to cooperate with a projecting lug 89 fixed to needle bar 50.

15 When the needle bar 50 is in raised position, as shown in Fig. 7, arms 81 and 86 serve to maintain the strands of the thread in proper alignment to prevent entanglement. When needle bar 50 moves downwardly a wedge-shaped needle chuck 20 90 fixed to the lower end of needle bar 50 acts so as to move arm 86 away from needle 52 against the action of spring 88 while at the same time lug 89 contacts the cam portion 85 to move arm 81 away from the needle against the action of 25 spring 83. Thus it is seen that arms 81 and 86 are caused to be spread apart to free the thread for effective use to permit the thread to be acted upon by a specially designed looper which will be described in detail as the description proceeds. 30 When needle bar 50 returns upwardly, arms 81 and 86 re-engage the needle 52 to hold the strands of the thread.

Another thread holding mechanism is also provided to hold the strands of the thread when the needle is connected to the lower needle bar 51. Referring to Fig. 3, there is disclosed a cam member 91 fixed to rocker arm 54. Cam member 91 is provided with a slotted portion 92. A link 93 is pivotally connected to the machine casing at a point 94, said link 93 having fixed thereto a pin 95 adapted to engage the slot 92 to cause link 91 to travel in an oscillatory path about pivot 94 whenever rocker arm 54 is moved. A forked member 96 is pivotally attached to link 93 at 97 at one end, and to a link 98 at a point 99. Link 98 is pivoted to the machine casting at 100, as shown in detail in Fig. 10. Forked member 96 has extension arm members which are adapted to straddle and press against the needle 52 at opposite sides thereof to maintain the thread in proper alignment to prevent entanglement. Cam member 91 is so designed as to maintain the lower thread holding mechanism, as just described, in effective position until such time as the thread is acted upon by a specially designed thread puller, similar to that shown and described in our Patent No. 1,931,447 and which will be discussed more fully as the description proceeds.

To further increase the efficiency of operation of our stitching machine, we have devised a novel mechanism which we call a looper, the operation of which will now be explained. Referring first to Fig. 7 of the drawings, there is disclosed a looper 105 one end of which is pivotally mounted to the machine casing at a point such as 106. Journaled in said machine casing is a shaft 107 (see also Fig. 1) having mounted thereon at one end a link 108. Said link 108 is connected to looper 105 by means of a link 109 one end of which is pivotally fastened to looper 105 at a point such as 110, the other end being pivotally connected to link 108 at 111. Thus it can be seen that when shaft 107 is rotated looper 105 will be caused to oscillate about

5 pivot 106. The degree and regularity of this oscillation may be governed by rotatably mounting on shaft 107 a roller 112 adapted to ride on a cam 37 and rigidly connected to shaft 107 by a link 115. The contour of cam 37 may be such as to cause looper 105, through the linkage system just described, to oscillate about pivot 106 at predetermined intervals to engage the loose end of the thread to form a loop. Looper 105 may be caused to pull the loose end of said 10 thread by any suitable hook means such as spool-like projection 116 (see Fig. 3). From the above description of the operation of the looper it becomes apparent that the loose end of the thread T is prevented from becoming entangled and 15 broken when the needle 52 is shifted from the upper needle bar, as in Fig. 7, to be clutched by the lower needle bar as shown in Fig. 10. The mechanism for operating the looper 105 just described is designed to act in cooperative relation with the thread holding means hereinbefore described in connection with the upper needle bar 50.

The mechanism which we employ in our improved apparatus to engage the loops as they 20 are formed from the thread in stitching and to draw or pull out the free end portion of the thread after each stitch may be similar to that shown and described in our Patent No. 1,931,447, hereinbefore mentioned. The operation of the 25 above-described mechanism will be clearly understood from a study of Figs. 3 and 7 of the drawings in which it is seen that gear 36 is mounted for rotation with pulley 32, and that when said gear 36 is rotated it causes a thread 35 puller 120 to be carried in a circular path around the periphery of a stationary grooved drum 121, by means of a chain of gears 122 (Fig. 3), 122', 123 and 124.

The following mechanism may be employed 40 to cause thread puller 120 to travel in its circular path: Gear 124 is so mounted that it is in eccentric relation to the axis of the grooved drum 121. Fixed to gear 124 for rotation therewith is an annular plate 124'. The thread 45 puller 120 is fixed to the outer end of a carrier arm 125, said carrier arm being pivoted at its inner end to the drum 121 at a point 126 coincident with the center of said drum 121. Carrier arm 125 is provided with a longitudinal slot 50 127 into which a block 128 fixed to the outer edge of annular disc 124' is adapted to slide. Thus it is seen that when gear 124 is rotated, the thread puller 120 is caused to travel around drum 121. The mechanism for operating the 55 thread puller as just described is designed to act in cooperative relation with the thread holding means hereinbefore described in connection with the lower needle bar 51.

The function of the stationary circular grooved drum 121 is similar to that shown and described in our Patent No. 1,931,447. Briefly stated it is to support the loose portion of the thread on the periphery of said drum 121 after the said thread has been pulled out from the fabric by 60 the thread puller 120. Figs. 11 and 13 clearly illustrate two steps in this action. Drum 121 may be provided with grooves 129 as shown in Fig. 12, to prevent entanglement of adjacent 65 strands of the thread while they rest on said drum 121. To further safeguard against the possible entanglement of the loose portion of the thread while it is being guided on to drum 121 and into grooves 129, we have devised a novel 70 thread holding means which may comprise a plu- 75

rality of brushes 130 held in engagement with grooves 129 of the drum 121 by means of adjustable springs 131 (see Fig. 9). Brushes 130 are pivotally fastened to the machine casing at suitably positioned points, such as at 132. These brushes 130 serve to hold the thread in its own groove on the drum 121 to prevent sagging and resulting entanglement. The looper 120 is adapted to readily pass through the brushes 130 as it travels in a circumferential path around said drum.

We have also devised a simplified and more efficient mechanism than heretofore employed for intermittently advancing the platform carrying the fabric to be stitched.

By referring to the drawings, the operation of the above mentioned mechanism will be clearly understood. In Fig. 7 we have disclosed a portion of the work carriage or the traveling platform 73 adapted to travel along any suitable guide means or tracks, such as shown and described in our Patent No. 1,931,447. On the underside of said platform 73 there is provided a toothed rack 135. On a shaft 137 fixed to the machine casing C we mount a gear 136 designed to mesh with said rack 135. The means by which gear 136 may be intermittently rotated to intermittently advance the platform 73 may be described as follows: On the shaft 137 we also mount a notched wheel 138 having a series of spaced notches 140 arranged circumferentially of said wheel 138. Mounted for rotation with gear 122' is a cam member 141 having an extended portion 142 adapted to cooperate with slots 140. Cam member 141 is so designed that with each revolution thereof the extended portion 142 will successively engage a slot 140 to rotate wheel 138 a predetermined amount. Wheel 138 will then rotate shaft 137 and gear 40 136 mounted thereon to advance platform 73 a predetermined distance in the direction shown by the arrow. Gear 122' is mounted on the same shaft as gear 122 and rotates therewith. Gear 122 is driven by gear 36 which in turn is fixed 45 to the pulley 32 for rotation therewith. The mechanism just described is so designed as to cause platform 73 to travel a predetermined amount after each stitch.

It is well known by those familiar with the art that the needle employed in machines of the type described must be occasionally changed for various reasons. It is desirable, therefore, that this be done as quickly as possible. To facilitate the quick removal and replacement of the needle, we have devised a mechanism which will now be described. Referring first to Fig. 5, we have shown an enlarged view in section of the mechanism of the upper needle bar 50 to which is screwed at its lower end a tapered chuck 90. Within the hollowed interior of chuck 90 we provide three balls B (see Fig. 6) arranged so as to permit needle 52 to be inserted between them and held thereby. When the balls B are pressed downwardly the tapered portion of chuck 90 forces them together to grip the needle 52. This downward pressure is applied by means of a spring 150 pressing against a shank 151 which in turn presses on the ball B. The upper end of said spring 150 abuts against a member 152 screwed into the top portion of needle bar 50. The upper end of shank 151 extends through member 152 and is fixed to a stop 153 the lower end of which is provided with a hollow portion adapted to allow needle bar 50 to slide therein. Thus it can be seen from the above

description that when the stop 153 is raised in the direction of the arrow while needle bar 50 is held stationary, it will carry with it shank 151. This will act so as to release the pressure on balls B to allow the needle 52 to be easily removed and replaced. Any suitable means for raising the stop 153 may be employed, such as a forked handle 155 (Figs. 7 and 8) pivotally mounted in a frame 156 fixed to the machine casing C. When handle 155 is pressed downwardly the lower forked end of said handle will engage the underside of stop 153 to raise the same and thereby release needle 52 in the manner just described.

It has been found in the course of the operation of stitching machines of the character described where the upper and lower needle bars are in alignment that occasionally the thread would be found to overlie the hole of the lower chuck so that when the needle travels downwardly to be grasped by the lower chuck it is apt to pierce the thread which interrupts its path, to break said thread. This obviously causes a delay inasmuch as it then becomes necessary for the operator to stop the machine and rethread the needle and start all over again. We have devised a novel means for overcoming this disadvantage which consists in positioning the needle hole in the lower needle chuck 90' to one side of the pointed portion thereof. By 30 this construction it is seen that the thread T is not able to rest over the needle hole in lower chuck 90' but will tend to slide down to either side due to the pointed construction as well as the positioning of the needle hole.

When operating machines of the character described by power means, such as a motor, it has been found desirable at times for certain reasons such as making trial stitches, to operate the machine by hand. The means by which we accomplish this in connection with our apparatus may be described as follows: Positioned within the central portion of pulley 32 is a clutch mechanism 160 shown in detail in Fig. 4. This mechanism operates on a principle similar to that used in free wheeling devices. A disc member 163 of the clutch 160 is rigidly attached to a collar 161 which idles on shaft 33. A plurality of spaced notched portions 162 are cut out of the circumference of disc 163. Into these notches are fitted rollers 164. It will be noted that disc 163 is of lesser diameter than the interior opening in pulley 32, thus permitting said disc 163 to rotate freely within the pulley 32. Fastened to the disc portion 163 of the clutch 160 at one end is a hand wheel 39 as shown in Fig. 3, adapted to rotate with said disc 163.

It will be seen from the above described construction that whenever the hand wheel 39 is rotated in a clockwise direction as indicated by the arrows in Figures 3 and 4, the rollers 164 will be held in notched portions 162 and disc 163 will be permitted to rotate freely without affecting the rotation of pulley 32. However, when the hand wheel 39 is rotated in a counter clockwise direction opposite to that shown by the arrows in Figures 3 and 4, rollers 164 will then be freed from the notched portions 162 to engage the inner surface of pulley 32 to lock disc 163 to said pulley for rotation therewith. Thus it is seen that whenever it is desired to operate the stitching machine by hand, it is merely necessary to turn the hand wheel in a direction opposite to that shown by the arrows in Figures 3 and 4 and in so doing, the machine will operate similarly to

that of the operation when power means is used.

Should it be desired to operate our apparatus automatically, we have provided an automatic switching mechanism adapted to close a circuit 5 to start the motor when a lever mechanism is tripped and to cause said circuit to be broken to stop the apparatus when the work platform has traveled a predetermined distance.

In Fig. 18 we have shown a wiring diagram 10 illustrating one means for accomplishing this result. When lever 170 is turned in the direction of the arrow B, a catch mechanism 171 is tripped to close the contacts 172 of the switch S by means of a spring R in order to complete a circuit from 15 a source of current supply through the motor M which is energized to cause platform 13 to travel in the direction of arrow A. Fastened to platform 13 and traveling therewith is a projecting lug 173 adapted to strike against a projecting portion S' of switch S. Lug 173 may be positioned at a predetermined distance from the projecting portion of switch S', such for example as is necessary for the complete stitching of a tie. When lug 173 strikes projecting portion of switch 20 S', contacts 172 are opened against the action of the spring R to break the circuit and stop motor M. The lever 170 may then be made to re-engage catch 171 to hold contacts 172 open until it is desired to operate the machine to stitch another tie.

It will thus be seen that there is provided a device in which the several objects of this invention are achieved, and which is well adapted to meet the conditions of practical use.

As various possible embodiments might be made of the above invention, and as various changes might be made in the embodiment set forth, it is to be understood that all matter herein set forth or shown in the accompanying drawings, is to be interpreted as illustrative and not in a limiting sense.

We claim:

1. In a sewing machine, the combination of 45 alternately operating needle bars, a support for said needle bars, a needle, means to alternately connect the needle with each needle bar, means for threading the needle, said last named means being mounted directly on one of said needle bars for movement therewith, means for securing one 50 end of a thread for the needle, and means whereby said needle threading means actuates said thread securing means.

2. In a sewing machine, the combination of a 55 needle, a needle bar cooperating with said needle, a support for said needle bar, means for threading the needle, said last named means being mounted directly on said needle bar for movement therewith, means for securing one end of a 60 thread for the needle, and means whereby said needle threading means is caused to actuate said thread securing means.

3. In a sewing machine, the combination of a 65 needle, a needle bar cooperating with said needle, a support for said needle bar, means for threading the needle, means for securing one end of a thread for the needle, a traveling work supporting platform, means whereby said needle threading means is caused to actuate said thread securing means to secure said thread, and means whereby 70 said thread securing means is actuated to release said secured thread after said platform has traveled a predetermined distance.

4. In a sewing machine, the combination of a 75 needle, a needle bar cooperating with said needle, means for threading the needle, means for se-

curing one end of a thread for the needle, a traveling work supporting platform, means whereby said needle threading means is caused to actuate said thread securing means to secure said thread, and means whereby said thread securing means 5 is actuated to release said secured thread after said platform has traveled a predetermined distance, said last named means being supported on said platform.

5. In a sewing machine, the combination of 10 a needle, a frame, a needle bar mounted on said frame and adapted to cooperate with said needle, said needle bar having a shoulder adjacent its upper end, manually manipulatable means associated with one of said needle bars for quickly 15 disconnecting the needle from said needle bar comprising a handle pivotally mounted on said frame adapted to engage the underside of said shoulder of said needle bar to raise the same, and means whereby said needle is caused to be 20 released when said needle bar is raised by said handle.

6. In a sewing machine, the combination of 25 alternately operating needle bars, a support for said needle bars, a needle, means to alternately connect the needle with each needle bar, a thread threaded through said needle and having one end secured and the other end free, said needle and needle bars adapted to form successive loops in 30 the thread, a puller for engaging said successive loops away from the needle and pulling out the free portion of the thread, means for driving said puller, a stationary drum cooperating with said puller and adapted to receive said free portion of 35 the thread thereon to prevent entanglement of said free end of thread, and means comprising a brush cooperating with said drum to hold said free end thread portions thereon.

7. In a sewing machine, the combination of 40 alternately operating needle bars, a support for said needle bars, a needle, means to alternately connect the needle with each needle bar, a thread threaded through said needle and having one end secured and the other end free, said needle and needle bars adapted to form successive loops in 45 the thread, a puller for engaging said successive loops away from the needle and pulling out the free portion of the thread, means for driving said puller, a stationary drum cooperating with said puller and adapted to receive said free portion of 50 the thread thereon to prevent entanglement of said free end of thread, and means cooperating with said drum to hold said free end thread portions thereon, said last named means comprising a brush adapted to be held in resilient engagement with the periphery of said drum.

8. In a sewing machine, the combination of 55 alternately operating needle bars, a support for said needle bars, a needle, means to alternately connect the needle with each needle bar, a thread threaded through said needle and having one end secured and the other end free, said needle and needle bars adapted to form successive loops in 60 the thread, a puller for engaging said successive loops away from the needle and pulling out the free portions of the thread, means for driving said puller, a stationary drum cooperating with said puller and adapted to receive said free portion of 65 the thread thereon to prevent entanglement of said free end of thread, and means cooperating with said drum to hold said free end thread portions thereon, said last named means comprising a brush adapted to be held in resilient engagement with the periphery of said drum, said 70

75

drum being provided with circumferential grooves.

9. In a sewing machine, the combination of alternately operating needle bars, a support for said needle bars, a needle, means to alternately connect the needle with each needle bar, a traveling work supporting platform, means timed with the alternately operating bars for intermittently advancing the platform, said means comprising a gear rack mounted on said platform, a gear co-operating with said rack, said gear being mounted on a shaft for rotation therewith, a wheel having a plurality of notches arranged circumferentially thereof and mounted on said shaft for rotation therewith, and means for successively engaging said notches to cause said wheel to rotate intermittently.

10. In a sewing machine, the combination of alternately operating upper and lower needle bars, a support for said needle bars, a needle, means to alternately connect the needle with each needle bar, a thread associated with said needle, each of said needle bars being provided with a substantially cone shaped chuck having a hole therein adapted to permit the needle to enter to be connected thereto, said upper and lower needle bar holes being in alignment, the hole in said lower needle bar being eccentric with respect to the apex of said cone whereby said needle is adapted to travel from said upper needle bar to said lower needle bar without piercing said thread to break the same.

11. In a sewing machine adapted to sew threads of predetermined length, the combination of alternately operating needle bars, a support for said needle bars, a needle, means to alternately connect the needle with each needle bar, and means for threading the needle, said last named means comprising a rigid member having one end thereof pivotally mounted on one of said needle bar and having the free end thereof provided with a hook adapted to pierce the eye of the needle, the radius of pivotal movement of said hook portion being substantially equal to the distance between the pivotal axis of said member and the eye of the needle.

12. In a sewing machine, the combination of alternately operating needle bars, a support for said needle bars, a needle, means to alternately connect the needle with each needle bar, one of said needle bars having a spring pressed member slidably relative thereto, and means for quickly disconnecting the needle from said needle bar, said last named means comprising a member pivotally mounted on said support, said member being provided with a cammed portion adjacent one end thereof and adapted upon pivotal movement of said pivotally mounted member to slidably move said spring pressed member against the action of its spring.

CERTIFICATE OF CORRECTION.

Patent No. 2,213,965.

September 10, 1940.

RUDOLF NAFTALI, ET AL.

It is hereby certified that error appears in the printed specification of the above numbered patent requiring correction as follows: Page 6, second column, line 9, claim 11, for the word "bar" read --bars--; line 20, claim 12, before "relative" insert --movable--; and that the said Letters Patent should be read with this correction therein that the same may conform to the record of the case in the Patent Office.

Signed and sealed this 5th day of November, A. D. 1940.

Henry Van Arsdale,
Acting Commissioner of Patents.
